UNITED STATES PATENT OFFICE.

LYMAN R. ROBERTS AND CHARLES L. DAVIS, OF DETROIT, MICHIGAN, ASSIGNEES TO
UNDERWOOD TYPEWRITER COMPANY, OF NEW YORK, N. Y., A CORPORATION OF
NEW JERSEY.

AUTOMATIC TYPE-WRITER ACTUATOR.

1,109,597.

Specification of Letters Patent. Patented Sept. 1, 1914.

Application filed April 20, 1908. Serial No. 428,050.

To all whom it may concern:

Be it known that we, LYMAN R. ROBERTS and CHARLES L. DAVIS, citizens of the United States, residing at Detroit, county of Wayne, State of Michigan, have invented certain new and useful Improvements in Automatic Type-Writer Actuators, and declare the following to be a full, clear, and exact description of the same, such as will enable others skilled in the art to which it pertains to make and use the same, reference being had to the accompanying drawings, which form a part of this specification.

This invention relates to typewriter operators, and has for an object the provision of an improved operating machine adapted to be employed in conjunction with a typewriter of standard make, that is, any typewriter of the key lever character.

The operator comprises a plurality of mechanically actuated hammers properly arranged to engage with those parts of a typewriting machine that are struck by the fingers of the operator; it contains some other actuating parts for shifting the various movable parts of the typewriter, as the carriage, the colored ribbon shift, and such other parts of the ordinary typewriter as may be actuated by the hand of the operator in some other way than by striking a blow upon a key tablet.

The operator hereinafter described, is one which is specially adapted to key actuated typewriters having what is known as the standard key board, in which there are generally from forty to forty-four character keys, one or two platen shift keys, a space bar, tabulating keys, etc., and in which the paper carrying carriage and platen traverse the frame, carrying the paper over the stroke point of the keys, and then retraverse the frame to return the carriage to its initial point.

The machine hereinafter described is provided with means for producing the actuation of the several parts of the typewriter from either of a plurality of control sheets, or master-letters, (using this term to mean a perforated sheet which acts to control the various movements of the movable parts of the machine.) One of these so-called master-letters contains perforations which control the writing of the body of a letter, and another so-called master sheet contains the controlling means for insets that are in-

serted in the main writing. To make this clear, suppose it be desired to write a large number of letters, each of which contains the same text, but each of which is addressed to a different individual, or in some of which there are to be insets containing matter that is not contained in other letters. In this case, there are two so-called master sheets, or master-letters, one of which will be in operation during the writing of the greater part, or body part, of the letter, while the second master-sheet will during this period be inactive, but at times, when the insets are to be written, or the addresses are to be written, the second master-letter will come into control, and the first, or main master-letter will be out of control. The master-letter in either case consists of a sheet of perforated paper similar in most respects to the sheet of perforated paper used in automatic mechanical music players, and in the machine hereinafter described, these sheets of perforated paper are used as valves to control the admission of air through a tracker board into a primary pneumatic, in which a valve is shifted that permits the action of a stronger air force through a secondary pneumatic which in turn controls the action of a power pneumatic, or hammer throwing bellows. The hammer, which in this case is a vertically reciprocating rod, strikes the key of the typewriter, and actuates the type key, or other type mechanism precisely as the finger of the human operator actuates the key. Some of the pneumatics, instead of actuating hammers, actuate levers, which produce some of the shifting movements.

The carriage travels forward under the ordinary spring power governed by the escapement actuator of the typewriter, and is returned by a screw or worm mechanism that is brought into operation at the proper time by a pneumatic governed by the master-letter. After the return of the carriage to its initial point, the screw connection is automatically thrown off by attachments which are connected with the screw itself.

When the typewriter is brought into position for operation in connection with the operator, the only coupling up of the two machines necessary is to engage an arm attached to a traveling nut or toothed member on the screw or worm to the space lever, which is that part of the typewriter con-

nected with the carriage which the operator grasps with his hand for the purpose of simultaneously making line feed of the paper, and pushing the carriage back to its starting point on the line.

No attention need be paid to starting the carriage at any particular point, as after the connection is made, and the power connection made by which the instrument is 10 actuated, the master-letter controls the proper location of the carriage, both for line feed of the paper, and for locating the carriage properly for the first stroke of the key on the paper to be printed. The master-letter is an endless strip, has continuous forward travel, and no attention need thereafter be paid to the machine except to see that it be filled with paper to be written on, and that the ink ribbon of the machine 20 be in suitable condition for good work. In other words, nothing is required for the further action of the machine than inspection from time to time, and the machine will then write and repeat the letter of the master-letter, inserting at proper places the insets of the second master-letter, repeating the same so long as power continues to be applied to keep it in movement. The presence of the paper in the typewriter is unimportant to the action of the machine. Of course the use of the machine without the paper is useless and destructive to the typewriter itself.

In the drawings which accompany this: 35 Figure 1, is a view of the assembled machine. Fig. 2, is a front elevation of the mechanism, (the front here meaning that side which is next to the typewriter, and at the right in Fig. 1). Fig. 3, is a detail elevation of two key actuators. Fig. 4, is a detail elevation of the mechanism which controls the movement of the master-letters. Fig. 5, shows the means for shifting the operation from one master-letter to another. 45 Fig. 6, is a detail of the valve construction of the primary and secondary pneumatic. Fig. 7, is a side elevation of the half-nut which returns the carriage. Fig. 8, is a detail of a portion of a master-letter. Fig. 9, is a detail of the release which disengages the half nut from the return screw. Fig. 10 is a detail perspective of the line-space mechanism. Fig. 11 is a sectional side elevation of the typewriter operator. 55 The movable parts are actuated partly by the direct action of a mechanical motor, applied to a master-wheel 1, and partly by means of pneumatic motors that are themselves actuated primarily by the master-wheel 1. The pneumatics are actuated by means of an exhaust pump or bellows 3 and 4, of which the one part 3 is expanded and contracted by a pitman 5, actuated by a crank 6 on crank shaft 16 of the wheel 17. 60 The part 4 of the exhaust bellows is nor-

mally held expanded by spring 41, and in contracting exhausts air through the pipe 7 from the various primary and secondary pneumatics and power pneumatics of the machine; to this end the exhaust pipe 7 is in 70 continuous free connection with air chambers 71, that underlie the several primary and secondary pneumatics. The exhaust bellows 4 maintains an exhaust condition in the chamber 71, and enables the air external 75 to the various pneumatics to actuate the same when the master-letter is in such relation to the tracker-board, hereinafter mentioned, as to allow a small portion of air to pass through the tracker-board to actuate the diaphragm in the chamber 8; this air may come through the tracker-board 9, or the tracker-board 91, depending upon the two master-sheets which are arranged to self-control this. The small amount of air 80 entering from the tracker-board lifts the flexible diaphragm 82, lifts the primary valve stem 83, closes the valve 84 against seat 85 in the primary case, lifts valve 86 from the casing 87, and admits external air 85 through opening 88, which transmits pressure through the passage 89, against diaphragm 72, and lifts the secondary valve stem 73 in the secondary casing. The chamber 90 of the secondary valve case is in continuous communication with the chamber of power pneumatic 61 (Fig. 3) through pipe 75, and with air chamber 71 when valve 76 is raised. The valve stem 73 lifts the valve 76 off from the diaphragm 77, opening a 100 passage from the valve chamber 80, into the chamber 8. At the same time the valve stem 73 lifts valve 78, closing it against a seat around an opening 79 through the case 74, and the exhaust now drawing through pipe 73, collapses the power pneumatic 61, and produces a plunger stroke which is utilized to actuate a type key or other part of the typewriting machine.

For each key of the typewriter to be 105 actuated, there is a vertically reciprocating hammer 50, which normally rests on, or just above, the key 52 of the typewriter when the typewriter is in position. When a perforation through the master-letter sheet registers with an opening of the tracker-board, air admitted through the tracker-board first 115 actuates the diaphragm 82 to shift the valves 84 and 86, following which the larger amount of air entering port 88 and passing through the pipe 89, actuates the diaphragm 72 to open port 77, and close the entrance for external air into the casing 74, after which the exhaust bellows 4 continuing in 120 action causes the power pneumatic 61 to collapse and produce the stroke of the hammer 50 upon the key 52; this is the equivalent to the stroke of the finger of a manual operator, and produces upon a typewriter all the 125 actuation which a stroke of the same key 130

would produce if made by a manual operator. The traveling and shifting movements of the typewriter are similarly produced, although in connection with some of them there are more intervening movable parts. The repeated action of the key hammers just described, or the successive action of a number of key hammers actuating different keys, produces the travel of the carriage, and the imprint of the letter upon the paper carried by the carriage.

After the carriage has reached its limit of travel, it is returned by mechanism which will be best understood from examination of Figs. 1, 2 and 4. Across the machine is a screw or worm 20, journaled in bearings in the side members A and B of the frame. This screw or worm is actuated from the shaft of the master-wheel 1, with which it is connected by means of a miter gear 11 on the said shaft, gear 12 on the vertical shaft 13, and miter gears 15 on the shaft 13 and the shaft of the screw or worm 20. The screw or worm is in constant rotation when the machine is in operation, and it is brought into actuating connection with the carriage by means of a half-nut 21 with which is connected an arm 22 which engages the line-space lever of the typewriter. The half-nut 21 has at least one tooth to engage between the threads or spirals of the screw or worm 20. With some typewriters, as for example the Underwood, the only arrangement necessary to make this connection is that the arm 22 be provided with a horizontal branch 23 through which there is a hole to engage over the upturned end of the line-space lever 266 shown in Figs. 4 and 10. This lever is pivotally mounted so as to actuate against the tension of the spring 268 the usual slide 267, which is provided with a pawl 269 engaging a ratchet wheel 270 connected to the platen 271 so as to rotate the same. To make connections between the operator and any other typewriter, this arm 22 is the only piece that needs to be changed in shape.

The half-nut 21 is carried at the lower end of an arm 21^a slidably mounted on a rocking guide frame comprising upper and lower horizontal rods 68 and 68^a, respectively, connected by upright arms 69, the lower rod 68^a being pivoted at its ends in the frame members A and B. The rod 68^a extends through an opening in the arm 21^a, thereby forming a pivotal support for the half-nut 21. The rod 68 of the rocking frame is adapted to bear against a roller 21^b on the arm 21^a and swing the half-nut into engagement with the screw 20.

During the forward or letter-feed movement of the carriage, the half-nut is held off the screw, and when the carriage has reached the limit of its travel, a perforation in the master-letter brings into action

a power pneumatic 63 (Fig. 4) which operates through the following mechanism, to connect the half-nut with the screw 20. The pneumatic 63 actuates a vertical rod 63^a similar to the hammer rod except that it is connected with a bell crank lever 64, one branch of which 65 is pivotally connected to a horizontal plunger 66. The free end of this plunger is normally supported on a pin 167 on a bracket 67, the plunger being provided with a stepped portion, such that after the plunger travels for a distance, it rises on the pin 167 which engages an inclined surface 168 leading from the under surface of the upper step to the under surface of the lower step. During its travel, and previous to the lifting motion, the end of the plunger strikes the rod 68 of the rocking guide frame.

The half-nut or toothed member 21 is normally out of engagement with the screw or worm, but is thrown into engagement with the screw or worm when the rod 68 is pushed over by the end of the plunger 66. This actuation of the plunger 66, and the consequent engagement of the half-nut with the return screw may be brought about at any time during the forward movement of the carriage, and is dependent entirely upon a perforation properly placed in the master-letter. Such a perforation is always placed at the end of a line of writing, and is also placed along the sheet at any place where it is desired to have a line of writing stop and the carriage return.

When the plunger 66 strikes the rod 68 and swings the frame over, the frame is automatically locked in its thrown-over position by a sliding block or catch 900 (Figs. 2 and 9) which lies behind an arm 69 of the rocking frame near the pivot rod 68^a. The block 900 has a thick portion 91 and a reduced portion 92, the latter when directly behind the arm 69 permitting the rocking frame to swing back and release the half-nut 21. When the pneumatically operated rod 66 swings the rocking frame and moves the half-nut into mesh with the screw 20 as above described, the block 900 is moved endwise by a coil spring 93, and brings the thick portion 91 behind the arm 69, thereby locking the swinging frame to hold the half-nut in running contact with the screw 20. Immediately after this locking occurs, the inclined face 166 of the rod 66 engages the pin 167, and lifts the end of the plunger rod 66 over the rod 68, and no longer obstructs the return of the frame, but the return movement of the frame is now prevented by the block or catch 900. The swinging frame is connected through a link 94 to a rock frame having rock arms 95 and 96, and the latter rock arm 96 engages under a hanging frame that carries the pressure roll 30, so that simultaneously with the

outward movement of the swinging frame, the pressure roll 30 is lifted off the feed roll or the master-letter, and the forward movement of the master-letter ceases. This 5 leaves the power pneumatic 63 under exhaust action because the forward movement of the master-letter has been stopped, and the opening through the master-letter which controlled the action of plunger 66 remains 10 in register with a duct through the tracker-board.

The exhaust action and consequent collapse of the power pneumatic 63 will continue so long as the master-letter continues 15 in place without movement, and movement of the master-letter must be started again by dropping the pressure roll 30. This is effected by the nut or toothed member 21 which, near the end of its travel along the 20 screw or worm 20, strikes the end 901 of the block or catch 900, and pushes the block or catch endwise against the spring 93 until the thick part of the block or catch 900 has passed out of engagement with the frame 25 of which the arm 69 forms a part, when the weight of the pressure roll 30, aided if necessary by a spring 301, (Fig. 9) causes the pressure roll 30 to drop its position of pressure engagement with the master-letter, 30 and advance the master-letter, bringing that into action again.

The half-nut 21 during its travel along the screw or spiral 20 not only returns the carriage, but also operates through the line-space lever 266 to rotate the platen a line-space distance, and at the same time place the returning spring 268 under tension. When the half-nut strikes the catch 900 and releases the rocking frame, the half-nut is 35 lifted from the screw 20 simultaneously with the return of the pressure roll 30, and permits the line-space lever 266, actuated by the spring 268, to return to normal position, which return movement carries the half-nut 40 21 a limited distance to the right along the screw shaft.

Should the master-letter be perforated to produce one or more additional line-space operations before the next line is written, the 50 next resulting movement of the paper brings another opening into proper arrangement to again collapse the power pneumatic 63, and again throw out the arm 69 and rock frame, whereby the running half-nut or toothed member again engages the screw or worm and runs until it strikes the block or catch 900, this movement of the half-nut again operating the line-spacer, and this action is 55 repeated to an extent which is determined by the perforations in the master-letter sheet. It may be repeated once, twice, or any number of times; frequently when passing from the end of one letter to the beginning of another over a printed letter-head it may be repeated several times.

The feed of the master-letter sheet over the tracker-board is produced by the rotation of a roll 101 over which the paper rolls. This roll 101 is driven by a pinion 102 which is on the same shaft with a friction driven 70 wheel 103. The friction driven wheel 103 is driven by a friction pinion 104 on the shaft 105, which shaft 105 is driven directly by the screw shaft 20 by means of the miter pinion 201, and more remotely by the main 75 driving wheel 1. The friction pinion 104 is adjustable along the shaft 105, across the face of the driven wheel to vary the speed of the master-letter over the roll 101. The travel speed of the master-letter controls all 80 the other operative parts.

The mechanism already described explains that part of the operator which is employed in making a print to follow the master-letter. In order that headings, addresses, etc., may be written on the same sheet, and as a part of the product letter, a second master letter sheet D is inserted over a second tracker-board 9. The rock arm 96 which lifts pressure roll 30 and thus controls the progress of master-letter C over feed roll 101, is connected by link 90 to lever arm 196 which lifts pressure roll 301 and thus controls the progress of master-letter D over feed roll 201, and any actuation of the rock frame comprising the arms 96 will lift both rock arms 96 and 196. Both pressure rolls are not, however, in operation at the same time, but always when one is in action as a pressure roll, the other is lifted 100 off from its pressure action on its own feed roll. The two feed rolls are in constant and equal action and are driven by the friction driven wheel 103, and a similar wheel 203 on the shaft of pinion 202. The wheels 103 and 203 are belted together. In order that the pressure rolls 30 and 301 may come into alternate action, the frames in which they swing are engaged by the two ends of an oscillating lever 204, (see Fig. 5) which 105 swings on a frame bar 200. One end of the lever with an interposed antifriction roll 205, engages under the arm 206 of the frame which carries the roll 30, and the other end with an interposed antifriction wheel 305 engages under the arm 306 of the frame which carries the pressure roll 301. The swinging lever 204 is actuated by a reciprocating bar 208 from power pneumatic 161, to which a collapsing movement is given in 110 consequence of a perforation in the master-letter sheet C. The reciprocating bar 208 strikes a pin 210 on the lever 204, pushes the lever over until the end of the lever, or the antifriction wheel on the end of the lever engages under the thick part or cam 211 on the arm 206, and lifts the pressure roll 30. At the same time, the lower antifriction wheel 305, passes from under the thick part or cam 311 on the arm 306, and 115 120 125 130

drops the pressure roll 301 into engagement with the feed roll 201. This brings into action the master-letter D, and causes the actuation of the operator in accordance with 5 the perforations on the master-letter D. When the shift to the master-letter C is desired, a perforation on the master-letter D causes the power pneumatic 162 to collapse, actuates the push bar 108, which strikes the 10 pin 110, drives the antifriction wheel 303 under the cam 311, lifts the frame 306 and pressure roll 301. In both cases the push bar 108 (or 208) rises and rides over the pin which it has engaged, so that it forms 15 no obstacle to the return action of the lever when the return action shall be required. The duct in tracker-board 91 through which the air that sets the valve to actuate power pneumatic 161 flows, is not connected up in 20 any way with the similar duct through the tracker-board 9, through which flows the air that acts to actuate the power pneumatic 162, but all other ducts in tracker-board 91 are joined by tubes that couple with Y- 25 couplings to corresponding ducts through tracker-board 9, that is, any of the operative power pneumatics connected with the tracker-board 9 is also connected with the tracker-board 91, except only those two 30 power pneumatics which shift the feed controlling rolls.

On most, if not all, of the standard typewriters which use a shifting carriage or a shifting platen, there are two keys 318, 319, 35 one of which when depressed, shifts the carriage or platen and locks it in its shifted position, and the other of which must be depressed in order to release this lock, or if the operator desires to shift for a single 40 capital, the operator generally depresses what may be termed the release key 319, which shifts but does not hold the platen in its shifted position. In this mechanical operator we employ two power pneumatics 320, 45 321, one of which 320 depresses the key which both shifts and locks, and the other of which 321 depresses the key which releases and when it is desired to write capitals we cause both these keys to be actuated. 50 The operation might be accomplished by using the single key which shifts but does not lock, but it requires some complications to properly time the movements which are unnecessary if we use the two keys. With 55 the use of two keys the timing is positive so that the platen is sure to get back to its proper place before another key strikes the platen after the capital type has made its impression.

60 The master sheet is preferably formed as an endless band which travels continuously forward over the feed roll, the slack drops into a box like receptacle G; no storage rolls or provision for winding or rewinding is 65 necessary. Both master sheets, or all the

master sheets when more than a single sheet is used, may drop into the same receptacle.

The entire structure may be briefly characterized as one that contains a principal or primary motor which maintains a constant 70 motion of some parts of the machine, a number of secondary motors each of which is or may be brought into intermittent motion, and a selector mechanism which is adapted to shift some part of the main power to the 75 selected dependent motor. The master wheel comprises this primary motor; this keeps in constant motion the carriage return screw, the feed rolls and the main air bellows. The selector mechanism comprises the 80 tracker board and the feed roll whose proper selective action takes place however only when a master-letter sheet is in co-action with them. The numerous secondary motors are actuated by the primary motor, but their 85 time of action and their period of action depend upon the selector. These three divisions comprise the entire machine except the single secondary spring motor which interposes an obstacle in the path of and prevents 90 the immediate return of the oscillating frame which couples up the carriage, and the carriage return screw, and thus serves to temporarily suspend the advance of the master sheet.

95 It will thus be seen that the various parts of the typewriter have individual pneumatic actuators, and that these actuators are controlled in their action from any one of a plurality of control sets, in this instance two 100 being shown. The control sets each include a tracker or tracker-board and a master sheet or member for each tracker with unidirectional feeding means for moving the master sheets past the trackers; the feeding 105 means being arranged to alternate in action so that one master sheet is stationary while the other is active. As shown in this instance, the master sheets have their general uniform character interrupted at a plurality of succeeding points by perforations 110 to correspond with the individual pneumatic actuators, and thus with the individual parts of the typewriter. The initial point of the endless master sheet, corresponding to the 115 first typewriting action in the typewritten piece of work effected under the control of this master sheet, comes after the final point of the master sheet corresponding to the last typewriting action in said typewritten 120 piece of work, so that the unidirectional feeding means for this endless master sheet can cause the same to effect an unlimited number of representations of a definite sequence of actions of the parts of the typewriter.

125 Variations may be resorted to within the scope of the invention, and portions of the improvements may be used without others.

What we claim is:-

1. A typewriter operator including a plu. 130

rality of pneumatic tracker boards, individual actuating means for actuating the several members of the typewriter, and pneumatic connections from each tracker board to each actuating means, whereby the actuation of the typewriter can be controlled from any tracker board.

2. A typewriter operator including a plurality of pneumatic tracker boards, individual actuating means for actuating the several members of the typewriter, pneumatic connections from each tracker board to each actuating means, whereby the actuation of the typewriter can be controlled from any tracker board, and means whereby any tracker board may be brought into requisition for operating the typewriter.

3. A typewriter operator in which a plurality of pneumatic master sheets operate alternately over a plurality of tracker boards, the sheets controlling a shifting mechanism to cause either sheet to become effective and stop the other sheet.

4. The combination with a typewriter, of an operator including a power-driven master wheel, pneumatics having means to operate said typewriter, a traveling perforated sheet adapted to act as a control for the air actuating said pneumatics, means for advancing said perforated sheet, and pneumatic means for stopping the advance thereof controlled by a perforation through said sheet.

5. The combination with a typewriter, of an operator including a plurality of pneumatics having means to operate said typewriter, a plurality of perforated master sheets to control the air pressure actuating said pneumatics, and pneumatic means controlled by said sheets for automatically shifting the control from one to another of said master sheets and causing them to stop and advance in alternation.

6. The combination with a typewriter having a carriage, of a main actuator, a pneumatic selector mechanism to operate said typewriter, a carriage return actuator, a pneumatic to bring said carriage return actuator into engagement with the typewriter carriage, and means for suspending the action of said selector mechanism.

7. In combination with a typewriter, a pneumatic typewriter operator provided with two separately acting pneumatic master sheets, two tracker boards, common means connected to the tracker boards to control the operation of said typewriter, and pneumatic means connected to said tracker boards whereby either master sheet may cause the cessation of its own action and simultaneous commencement of action of the companion master sheet.

8. The combination with a typewriting machine, of pneumatic means for causing the actuation of the several parts of the

typewriting machine by either of a plurality of control sheets, one of which is endless, and each of which stops itself and starts the other, a plurality of tracker boards, and common connections to the pneumatics.

9. The combination with a typewriting machine, of a pneumatic actuator, for operating said typewriter, said actuator having a control sheet for writing the text of a document, and an endless control sheet prepared to write insets in the document, each sheet stopping itself and starting the other, a plurality of tracker boards, and common connections to the pneumatics.

10. The combination with a typewriting machine, of an actuator having a plurality of control sheets, one of which is prepared for writing the text of a letter document, and the other of which is endless and prepared to insert different names or addresses in the document, means for calling said control sheets into operation in alternation, and pneumatic means controlled by either sheet for operating said typewriting machine, including a plurality of tracker boards and a set of pneumatics common to said tracker boards and operating the typewriting machine.

11. The combination with a typewriting machine, of a pneumatic actuator having a plurality of control sheets, means being provided for enabling either sheet to cause the operation of said typewriter, and means controlled by the sheets for calling said control sheets into operation in alternation, and simultaneously bringing the other sheet to rest.

12. The combination with a typewriter, of a pneumatic operator having a plurality of tracker boards, and a set of pneumatics common to said tracker boards and having means for enabling either tracker board to control the operation of the typewriting machine, each tracker board having a pneumatic for calling the other into use.

13. The combination with a typewriter having operating members, of a pneumatic operator having a plurality of tracker boards, and means for enabling either tracker board to control the operation of the typewriting machine, said controlling means including a series of pneumatics, one for each of the typewriter operating members, and means for enabling the pneumatics to be controlled through either tracker board, each tracker board having a pneumatic for calling the other into use.

14. In a typewriter actuator, the combination with a plurality of tracker boards, of means for enabling either tracker board to control the operation of the typewriting machine, said controlling means including a series of pneumatics, one for each of the typewriter operating members, and means for enabling the pneumatics, each of said

- pneumatics consisting of a primary and a secondary pneumatic, to be controlled through either tracker board, each of said pneumatics being controlled by a primary 5 and a secondary pneumatic, each tracker board having a pneumatic for calling the other into use.
15. A typewriter actuator comprising a series of bellows, a series of hammers connected thereto, each hammer in the form of a vertically reciprocating rod, said rods arranged in banks over the keys of the typewriter, to strike down thereon.
16. In a typewriter actuator, the combination of a revolving screw extending across the machine parallel with the direction of travel of the carriage of the typewriter, power-driven means to revolve said screw, an exhaust device having power-driven 10 means which are connected to said screw, a nut normally disengaged from said screw and having an arm connected to the line-spacing and carriage-returning devices of the typewriting machine, a tracker board, a power pneumatic connected to said exhaust device and to said tracker board, means operated by said pneumatic to engage said nut with said screw to return the carriage, means to feed a control sheet over the 15 tracker board, means also operated by said pneumatic to arrest the feed of the sheet, and means operated by said nut when driven by said screw, to cause said sheet to resume its feeding.
- 35 17. In a typewriter actuator, the combination of a revolving screw extending across the machine parallel with the direction of travel of the carriage of the typewriter, power-driven means to revolve said screw, an exhaust device having power-driven 20 means which are connected to said screw, a nut normally disengaged from said screw and having an arm connected to the line-spacing and carriage-returning devices of the typewriter machine, a tracker board, a power pneumatic connected to said exhaust device and to said tracker board, means operated by said pneumatic to engage said nut with said screw to return the carriage, a power 25 driven roll, a pressure roll coöperating therewith to feed a perforated control sheet over the tracker board, means operated by said pneumatic to release said pressure roll, and means connected to said nut to restore 30 said pressure roll to normal position.
18. In a typewriter actuator, the combination of a revolving screw extending across the machine parallel with the direction of travel of the carriage of the typewriter, power-driven means to revolve said screw, an exhaust device having power-driven 35 means which are connected to said screw, a nut normally disengaged from said screw and having an arm connected to the line-spacing and carriage-returning devices of the typewriter 40 machine, a tracker board, a power pneumatic connected to said exhaust device and to said tracker board, means operated by said pneumatic to engage said nut with said screw to return the carriage, a power driven roll, a pressure roll coöperating 45 therewith to feed a perforated control sheet over the tracker board, means operated by said pneumatic to release said pressure roll, and means connected to said nut to restore 50 said pressure roll to normal position.
- 55 the typewriting machine, a tracker board, a power pneumatic connected to said exhaust device and to said tracker board, means operated by said pneumatic to engage said nut with said screw to return the carriage, a power-driven roll, a pressure roll coöperating therewith to feed a perforated control sheet over the tracker board, means operated by said pneumatic to release said pressure roll, and means controlled by said nut to maintain said nut in engagement with said screw, and means controlled by said nut to release itself from said screw and restore 60 said pressure roll to normal position to cause the feeding of the control sheet to be resumed.
19. In a typewriter actuator, the combination of a revolving screw extending across the machine parallel with the direction of travel of the carriage of the typewriter, power-driven means to revolve said screw, an exhaust device having power-driven 65 means which are connected to said screw, a nut normally disengaged from said screw and having an arm connected to the line-spacing and carriage-returning devices of the typewriting machine, a tracker board, a power pneumatic connected to said exhaust device and to said tracker board, a plunger connected to said pneumatic, an arm connected to said nut and operated by said plunger to engage the nut with the screw, said nut and its arm being carried upon a rocking guide-frame extending along said screw, a trip pressed by a spring into position to hold said frame when the latter is moved by said plunger to connect the nut to the screw, a part on said nut to press the trip back to release said frame, a spring to separate the nut from the screw, a power-driven roll, a pressure roll carried upon a frame and coöperating with the power-driven roll to feed the control sheet over the tracker board, and means connecting said roll frame to said guide frame to release the pressure roll simultaneously with the movement of the nut into engagement with the screw, and restore said pressure roll simultaneously with the separation of the nut from the screw.
20. In a typewriter actuator, the combination with a power shaft, of a screw shaft connected to said power shaft, a roll shaft also connected to said power shaft, a tracker board, a pressure roll to coöperate with said roll shaft to feed a master sheet over the tracker board, pneumatics connected to said tracker board and having hammers to operate the keys of the typewriter, a carriage drive-nut, a pneumatic also connected to the tracker board to connect said carriage drive-nut with said screw, means to arrest the feed of the control sheet during the return of the carriage, and means to cause the control sheet to resume feeding.

21. In a typewriter actuator, the combination with a power shaft and a bellows connected thereto, of a screw shaft connected to said power shaft, a roll shaft also connected to said power shaft, a tracker board, a pressure roll to coöperate with said roll shaft to feed a master sheet over the tracker board, pneumatics connected to said tracker board and having hammers to operate the keys of the typewriter, connections between the bellows and the pneumatics, a carriage drive-nut, and a pneumatic also connected to the tracker board to connect said carriage drive-nut with said screw; speed-regulating means being provided between the roll shaft and the power shaft.

22. In a typewriter actuator, the combination with a tracker board, of a power shaft, a screw shaft connected to said power shaft to be driven thereby, a roll shaft also connected to said power shaft, a tracker board, a pressure roll to coöperate with said roll shaft to feed a master sheet over the tracker board, a second tracker board, a second power driven roll also connected to said power shaft, a second pressure roll coöperating with said second power driven roll, to feed a second controlling sheet over the second tracker board, a set of pneumatics connected by Y-couplings to said tracker boards, and having hammers to operate the keys of the typewriter, a pneumatic also connected by a Y-coupling to the tracker boards to connect a carriage drive-nut with said screw, means to arrest the feed of the control sheets during the return of the carriage by means of said screw, and means to cause the control sheets to resume feeding.

23. In a typewriter actuator, the combination with a tracker board, of a power shaft, a bellows connected thereto, a screw shaft connected to said power shaft to be driven thereby, a roll shaft also connected to said power shaft, a tracker board, a pressure roll to coöperate with said roll shaft to feed a master sheet over the tracker board, a second tracker board, a second power-driven roll also connected to said power shaft, a second pressure roll coöperating with said second power-driven roll, to feed a second controlling sheet over the second tracker board, a set of pneumatics connected by Y-couplings to said tracker boards, and having hammers to operate the keys of the typewriter, a pneumatic also connected by a Y-coupling to the tracker boards to connect a carriage drive-nut with said screw, connections between the bellows and the pneumatics, means to arrest the feed of the control sheets during the return of the carriage by means of said screw, means to cause the control sheets to resume feeding, and means to enable either sheet to stop its own feed and start the feed of the other sheet.

24. In a combined typewriter and operator, the combination with a typewriter, of two tracker boards, pneumatic means to operate the typewriter, a power-driven roll for each tracker board, pressure rolls for said power-driven rolls, and a pneumatic connected to each tracker board and provided with means both to release its associated pressure roll and to call into action the pressure roll associated with the other tracker board.

25. In a typewriter operator, the combination with two tracker boards, of a power-driven roll for each tracker board, pressure rolls for said power driven rolls, and a pneumatic connected to each tracker board and provided with means both to release its associated pressure roll and to call into action the pressure roll associated with the other tracker board, frames on which said pressure rolls are mounted, said frames provided with roll-releasing cams, and a lever extending from one cam to the other to engage one while releasing the other, said pneumatics having means to vibrate said lever.

26. In a typewriter operator, the combination with two tracker boards, of a power-driven roll for each tracker board, pressure rolls for said power driven rolls, and a pneumatic connected to each tracker board and provided with means both to release its associated pressure roll and to call into action the pressure roll associated with the other tracker board, frames on which said pressure rolls are mounted, said frames provided with roll-releasing cams, and a lever extending from one cam to the other to engage one while releasing the other, said pneumatics having means to vibrate said lever, and said vibrating means comprising plungers and trips for the plungers.

27. In a typewriter operator, the combination with mechanism for operating certain parts of a typewriter, of a master sheet for controlling the operation of said mechanism, a friction disk connected so as to drive said master sheet, a shaft, and a friction pinion adjustable along said shaft and across the face of said disk, whereby the speed of said master sheet may be varied to control of the speed of said mechanism.

28. The combination with a typewriter, of a pneumatic typewriter actuator having a master sheet controlling its action and arranged to automatically run repeatedly, independent of manual shifting, through said actuator, so as to reproduce any number of times a predetermined sequence of operations of said typewriter by said actuator.

29. The combination with a typewriter, of a pneumatic typewriter actuator having a master sheet controlling its action and arranged to automatically run repeatedly, in-

dependent of manual shifting, through said actuator, so as to reproduce any number of times a predetermined sequence of operations of said typewriter by said actuator; 5 said actuator also having another master sheet for supplementing the control of said actuator by said first-mentioned sheet.

30. The combination with a typewriter, of a pneumatic typewriter actuator having a 10 master sheet controlling its action and arranged to automatically run repeatedly, independent of manual shifting, through said actuator, so as to reproduce any number of times a predetermined sequence of operations 15 of said typewriter by said actuator; said master sheet having certain passive periods, said actuator also having a second master sheet for supplementing the control of said actuator by said first-mentioned 20 master sheet by assuming the control during the passive periods of said first-mentioned master sheet.

31. The combination with a typewriter, of a pneumatic typewriter actuator having a 25 master sheet controlling its action and arranged to automatically run repeatedly, independent of manual shifting, through said actuator, so as to reproduce any number of times a predetermined sequence of operations 30 of said typewriter by said actuator; said master sheet having certain passive periods and means to control the change between its own active and passive periods.

32. The combination with a typewriter, of 35 a pneumatic typewriter actuator having a master sheet controlling its action and arranged to automatically run repeatedly, independent of manual shifting, through said actuator, so as to reproduce any number of 40 times a predetermined sequence of operation of said typewriter by said actuator; said master sheet having certain passive periods, said actuator also having a second master sheet for supplementing the control of said 45 actuator by said first-mentioned master sheet by assuming the control during the passive periods of said first-mentioned master sheet; said master sheets controlling the action of each other.

50. 33. The combination with a typewriter, of a typewriter actuator having an endless master sheet for reproducing a predetermined sequence of actions of said typewriter, feeding means for said sheet, and pneumatic 55 means controlled by said sheet for operating said typewriter, said master sheet being endless so that said feeding means can pass said master sheet repeatedly in the same direction through said actuator, so as to reproduce automatically any number of times 60 said predetermined sequence of actions of said typewriter; said master sheet controlling its own motion.

34. The combination with a typewriter in-

cluding a carriage and a platen and types, 65 of a typewriter operator for actuating said typewriter, including means for actuating the types, the carriage and the platen of said typewriter, a master sheet for controlling the operation of said operator, and a variable-speed driver for said master sheet controllable as to its speed so as to vary the speed of operation of said operator.

35. The combination with a typewriter, of an operator for said typewriter including a 75 master sheet for controlling the various parts thereof, and means for controlling the speed of movement of said master sheet from a single point, so as to control the speed of operation of other parts of said operator 80 from said single point.

36. The combination with a typewriting machine including a traveling carriage, of a typewriter operator for actuating said typewriting machine including a master record 85 for controlling the movements of said operator, means for returning said carriage, and means for suspending the movement of said master record during the return motion of said carriage. 90

37. The combination with a typewriting machine including a traveling carriage, of a typewriter operator for actuating said typewriting machine including a master record for controlling the movements of said operator, means for returning said carriage, means for suspending the movement of said master record during the return motion of said carriage, and means for starting the movement of said master record at the end 100 of the return movement of said carriage.

38. The combination with a typewriting machine including a platen, of a typewriter operator for actuating said typewriting machine including a master record for controlling the movements of said typewriter operator, means for rotating said platen, and means for suspending the movement of said master record during the rotation of said platen. 105

39. The combination with a typewriting machine including a platen, of a typewriter operator for actuating said typewriting machine including a master record for controlling the movements of said typewriter operator, means for rotating said platen, means for suspending the movement of said master record during the rotation of said platen, and means for starting said master record at the finish of the rotation of said platen. 115

40. The combination with a typewriting machine including a carriage having a platen thereon, of a typewriter operator for actuating said typewriting machine including a master record, and pneumatic means 120 controlled by said master record for rotating said platen.

41. The combination with the platen roll

- of a typewriter, of a worm, means for driving said worm, and pneumatically controlled mechanism operable to coöperate with said worm to impart retracting movements to the platen roll. 5
42. The combination with the platen roll of a typewriter, of a rotating worm, pneumatically controlled mechanism operable to coöperate with said worm to impart retracting movements to the platen roll, and means actuated by a part of said mechanism to impart line-spacing movements to the platen roll when said mechanism is actuated. 10
43. The combination with a rotating worm, of a carriage having engagement with the platen roll and capable of longitudinal movements therewith, a tooth movably carried by said carriage for engagement with the worm, and pneumatically operated mechanism for controlling the worm engaging and disengaging movements of said tooth to cause it to coöperate with the worm to retract the carriage and platen roll a predetermined distance. 15
44. The combination with a platen-roll, of a rotating worm, means having longitudinal movements with the platen-roll and having a relatively movable part for engagement with said worm to coöperate therewith to communicate retracting movements to said means and platen, and pneumatically operated mechanism for controlling the movements of said part to engage and disengage the worm at predetermined intervals. 20
45. The combination with the platen-roll of a typewriter, of rotatable means, a carriage attached to and movable with said platen-roll and having a part capable of movement to engage and disengage said means to coöperate therewith to move the carriage and platen-roll to retracted position, and pneumatically controlled mechanism operable to move said part to engage said means at predetermined intervals. 25
46. The combination with a platen-roll of a typewriter, of power means, mechanism normally disengaged from said power means, and adapted when engaged with said means to coöperate therewith to impart retracting movements to the platen-roll and pneumatically controlled mechanism to engage and release the power means at predetermined intervals. 30
47. The combination with the platen-roll of a typewriter, of a rotating worm, a carriage attached to and movable with the platen-roll and having a part for engaging with said worm to cause retracting movements to be communicated to the carriage and platen-roll from a rotation of said worm, a member acting on said part to normally retain it out of engagement with said worm and movable to place it into engage- 35
- ment therewith, and mechanism operable to automatically move said member to engage said part with the worm at predetermined intervals. 65
48. The combination with the platen-roll of a typewriter, of power means, a carriage attached to and movable with the platen-roll and having a part for engaging said power means to coöperate therewith to impart retracting movements to the carriage, a member acting on said part to normally retain it out of engagement with said power means and movable to effect its engagement with the power means, means automatically operable to move said member to place said part in engagement with the power means, catch means for holding said member in shifted position, and means automatically operable to release said catch means to permit a disengagement of said part and power means when the carriage has been retracted a predetermined extent. 70
49. The combination with the platen-roll of a typewriter, of power means, a carriage yieldingly attached to and movable with the platen-roll, means guiding the movement of said carriage, mechanism acting on a part of said carriage to normally hold said part out of engagement with the power means and automatically operable to move said part into engagement with said means to coöperate therewith to impart a retracting movement to the carriage and to release the engagement of said part and power means at a predetermined point in a retracting movement of the carriage, and pneumatic means for controlling the action of said mechanism. 75
50. The combination with the platen-roll of a typewriter, of a drive worm, a carriage movable with said platen-roll and having arms projecting therefrom and in thrust engagement with the opposite ends of said roll, a part carried by said carriage for engagement with the worm to coöperate therewith to move the carriage and platen-roll to line starting position, and mechanism automatically operable to move said part at predetermined intervals to engage and release said worm. 80
51. The combination with a rotating worm, of a platen-roll carriage capable of longitudinal movements, a platen-roll movable longitudinally therewith, a tooth, nut or follower movably carried by said carriage for engagement with the worm, mechanism for controlling the worm engaging and disengaging movements of said tooth to cause it to coöperate with the worm to retract the carriage a predetermined distance, and means actuated by a part of said mechanism to impart line spacing movements to the platen roll. 85
52. The combination with a platen-roll, 90
- 95
- 100
- 105
- 110
- 115
- 120
- 125

of a rotating worm, means having longitudinal movements with the platen-roll and having a relatively movable part for engagement with said worm to coöperate therewith to communicate retracting movements to said means and platen, automatically operable mechanism for controlling the movements of said part to engage and disengage the worm at predetermined intervals, and means actuated by a movement of said mechanism to impart line spacing movements to the platen roll.

53. The combination with the platen-roll of a typewriter, of rotatable means, a carriage attached to and movable with said platen-roll and having a part capable of movements to engage and disengage said means to coöperate therewith to move the carriage and platen-roll to retracted position, automatically controlled mechanism operable to move said part to engage said means at predetermined intervals, and means actuated by a part of said mechanism to impart line-spacing movements to the platen roll.

54. The combination with the platen-roll of a typewriter, of a rotating worm, a carriage attached to and movable with the platen-roll and having a part for engaging 30 with said worm to cause retracting movements to be communicated to the carriage and platen-roll from a rotation of said worm, a member acting on said part to normally retain it out of engagement with said 35 worm and movable to place it into engagement therewith, mechanism operable to automatically move said member to engage the worm at predetermined intervals, and line-spacing means actuated by a movement of 40 said mechanism.

55. The combination with the platen-roll of a typewriter, of power means, a carriage attached to and movable with the platen-roll and having a part for engaging said power means to coöperate therewith to impart retracting movements to the carriage, a member acting on said part to normally retain it from engagement with said power means and movable to effect its engagement with 45 the power means, mechanism automatically operable to move said member to place said part into engagement with the power means, catch means for holding said member in shifted position, means automatically operable to release said catch means to permit a 50 disengagement of said part and power means when the carriage has been retracted a predetermined extent, and line-spacing means actuated by a movement of said mechanism.

56. The combination with the platen-roll of a typewriter, of power means, mechanism normally disengaged from said power means and adapted when engaged with such means to coöperate therewith to impart retracting 55 movements to the platen roll, and pneumati-

cally operated perforated sheet controlled mechanism for engaging and releasing the power means at predetermined intervals.

57. The combination with the platen-roll of a typewriter, of power means, a carriage attached to and movable with said platen-roll and having a part capable of movement to engage and disengage said power means to coöperate therewith to move the carriage and platen-roll to retracted position, and mechanism automatically operable to move said part to engage said means at predetermined intervals.

58. The combination with a typewriter carriage, of a constantly driven member, master members, and a common means separately controlled by the master members for controlling the connection of said carriage with said driven member, so as to govern the traversing of said carriage.

59. The combination with a typewriter carriage, of a constantly driven member, and a plurality of means for separately controlling the connection of said carriage with said member, so as to govern the traversing of said carriage.

60. The combination with a typewriter carriage, of a constantly driven member, and a plurality of devices for pneumatically controlling the connection of said carriage with said member, so as to govern the traversing of said carriage.

61. The combination with a typewriter carriage, of a constantly driven member, automatic means comprising separately operable controlling devices for connecting and disconnecting said carriage with said member at predetermined points, to determine the period of movement of said carriage.

62. The combination with a typewriter having a keyboard, of a single set of pneumatic actuators for said keyboard, a plurality of control sets for said set of pneumatic actuators, and means for selectively shifting 110 the activity from one control set to another.

63. The combination with a typewriter, of a single set of actuators for operating the parts of said typewriter, an endless master sheet having its general character interrupted at a series of successive points corresponding to the operation of individual actuators to operate corresponding parts of said typewriter, so as to produce the body portion of a typewritten piece of work, said master sheet being endless so that the initial one of said points corresponding to the first typewriting operation of a piece of work can succeed the last of said points corresponding to the final typewriting operation 115 of a piece of typewritten work, whereby said endless master sheet by a continuous motion in one direction can effect a definite series of operations of the parts of said typewriter by said actuators over and over 120 125 130

again, and a second master sheet having several groups of points interrupting the general character thereof, each group corresponding to a separate insert to be made in the main portion of the typewritten piece of work.

64. The combination with a typewriter, of a single set of actuators for operating the parts of said typewriter, an endless master sheet having its general character interrupted at a series of successive points corresponding to the operation of individual actuators to operate corresponding parts of said typewriter, so as to produce the body portion of a typewritten piece of work, said master sheet being endless so that the initial one of said points corresponding to the first typewriting operation of a piece of work can succeed the last of said points corresponding to the final typewriting operation of a piece of typewritten work, driving means for feeding said master sheet repeatedly in one direction so as to effect a definite series of operations of the parts of said typewriter by said actuators any desired number of times, a second master sheet having several groups of points interrupting the general character thereof, each group corresponding to a separate insert to be made in the main portion of the typewritten piece of work, and feeding means for passing said second master sheet intermittently in one direction.

65. The combination with a typewriter, of a single set of actuators for operating the parts of said typewriter, an endless master sheet having its general character interrupted at a series of successive points corresponding to the operation of individual actuators to operate corresponding parts of said typewriter, so as to produce the body portion of a typewritten piece of work, said master sheet being endless so that the initial one of said points corresponding to the first typewriting operation of a piece of work can succeed the last of said points corresponding to the final typewriting operation of a piece of typewritten work, feeding means for feeding said master sheet repeatedly in one direction so as to effect a definite series of operations of the parts of said typewriter by said actuators any desired number of times, a second master sheet having several groups of points interrupting the general character thereof, each group corresponding to a separate insert to be made in the main portion of the typewritten piece of work, feeding means for passing said second master sheet intermittently in one direction, and shifting means for alternating the activity from one feeding means to the other.

66. The combination with a typewriter, of actuators for the several parts of said typewriter, a plurality of control sets for said actuators, each including a master sheet, and

individual feeding means for said master sheets, said feeding means alternating in action so that each master sheet will be stationary while another is in action.

67. The combination with a typewriter, of actuators for the several parts of said typewriter, a control set including a tracker, a repeat master sheet, and means for feeding the same portions of said master sheet repeatedly into co-operation with said tracker, means for rendering said feeding means ineffective so that said master sheet will remain stationary, and a control set for governing the action of said actuators while said repeat master sheet is stationary.

68. The combination with a typewriter, of actuating means for said typewriter, a master sheet for controlling the action of said actuating means, a power-driven roll for said master sheet, and a pressure roll movable into and out of engagement with said master sheet to enable the feeding of said master sheet by said power-driven roll.

69. The combination with a typewriter, of actuating means for said typewriter, a master sheet for controlling the action of said actuating means, a power-driven roll for feeding said master sheet, a pressure roll for holding said master sheet in engagement with said power-driven roll so that said master sheet can be fed thereby, shifting means for determining the action of said pressure roll, and means for controlling the action of said shifting means from said master sheet.

70. The combination with a typewriter, of actuating means for said typewriter, a master sheet for controlling the action of said actuating means, a power-driven roll for said master sheet, a pressure roll for holding said master sheet in close engagement with said power-driven roll, a shifting lever for determining the action of said pressure roll, and a pressure roll out of contact with said lever movable into contact therewith to shift the same.

71. The combination with a typewriter, of actuating means for said typewriter, a master sheet for controlling the action of said actuating means, a power-driven roll for said master sheet, a pressure roll for holding said master sheet in close engagement with said power-driven roll, a shifting lever for determining the action of said pressure roll, a pressure roll out of contact with said lever movable into contact therewith to shift the same, and a collapsible bellows for reciprocating said pressure roll.

72. The combination with a typewriter, of actuating means for said typewriter, a master sheet for controlling the action of said actuating means, feeding mechanism for said master sheet, shifting means for determining the action of said feeding means, and actuating means for said shifting means

movable into operative engagement with said shifting means and moving free and clear of said shifting means after having actuated the same.

5 73. The combination with a typewriter, of actuating means for said typewriter; a master sheet for controlling the action of said actuating means, feeding mechanism for said master sheet, shifting means for determining the action of said feeding mechanism, actuating means for operating said shifting means, and disconnecting means operating to force said last-mentioned actuating means free and clear of said shifting means after having operated the same.

10 74. The combination with a typewriter, of actuating means for said typewriter, a plurality of master sheets for controlling the action of said actuating means, feeding means individual to each of said master sheets, shifting means for determining which of said feeding means shall be effectively active, and a plunger individual to each of said feeding means for operating said shifting means.

15 75. The combination with a typewriter, of actuating means for said typewriter, a plurality of master sheets for controlling the action of said actuating means, feeding means individual to each of said master sheets, shifting means for determining which of said feeding means shall be effectively active, a plunger individual to each of said feeding means for operating said shifting means, means individual to each plunger for shooting it forward to actuate said shifting means and for holding it forward in its operated position, and diverting means for disconnecting said plungers from said shifting means after said plungers have actuated the same, so as to enable a free return of said shifting means subsequently.

20 76. The combination with a typewriter, of actuating means for said typewriter, a pair of master sheets for controlling the action of said actuating means, a tracker board individual to each of said master sheets, means for feeding said master sheets past said tracker board, and Y air conduits connecting each of said pneumatic actuators with both of said tracker boards, whereby any of said actuators can be controlled from both of said tracker boards.

25 77. The combination with a typewriter, of actuating means for said typewriter, a plurality of master sheets for controlling the action of said actuating means, unidirectional feeding means for always feeding each of said master sheets in a single direction, one of said master sheets being formed to effect a single complete piece of typewritten work, the other of said master sheets being formed to effect a plurality of separate inserts, and means for controlling said feeding means to change from control by

one master sheet to control by another master sheet.

78. A typewriter operator comprising a set of type-operating trains; a source of power permanently connected to said trains and tending constantly to operate them; a master sheet; an independent master sheet; and means to coöperate with said master sheets, to enable either of them to select the trains to be operated by said source of power.

79. A typewriter operator comprising a set of type-operating trains; a source of power permanently connected to said trains and tending constantly to operate them; a master sheet; an independent master sheet; means to coöperate with said master sheets or devices; to enable either of them to select the trains to be operated by said source of power, and means for advancing each master sheet and concomitantly suspending the advance of the other.

80 85 90 95 81. A typewriter operator comprising a set of type-operating trains, a source of power permanently connected to said trains and tending constantly to operate them, a plurality of tracker boards over which master sheets may run, and means extending from said tracker boards to said trains to coöperate with the master sheets to control the operation of the trains.

100 105 82. A typewriter operator comprising a set of type-operating trains, a source of power permanently connected to said trains and tending constantly to operate them, a plurality of tracker boards over which master sheets may run, and a connection ramifying from each of said trains to said tracker boards, to enable either master-sheet to control the operation of the train.

110 115 83. A typewriter operator comprising a set of type-operating trains, a source of power directly connected to said trains and tending constantly to operate them, a master sheet, a second master sheet, means to coöperate with said master sheets, to enable either of them to select the trains to be operated by said source of power, advancing mechanisms for said sheets, and means, also under the control of said master sheets, for silencing either sheet-advancing mechanism and concomitantly causing the other sheet-advancing mechanism to resume operation.

120 125 130 84. A typewriter operator comprising a set of type-operating trains, a source of power directly connected to said trains and tending constantly to operate them, a master sheet, a second master sheet, means to coöperate with said master sheets to enable either of them to select the trains to be operated by said source of power, feeding or advancing means being provided for said master sheets, controlling mechanism for said feeding means to start and stop the sheets in alternation, and power-driven

means under the control of said sheets tending constantly to operate said controlling mechanism.

84. A typewriter operator comprising a set of pneumatics, type-operating trains, a plurality of tracker boards, connections from each pneumatic to said tracker boards, the connections between the type-trains and the tracker boards being permanent in character, whereby the control of the type operating trains by the tracker boards is made absolute and master-advancing mechanism associated with each of said tracker boards.

85. A typewriter operator comprising a set of pneumatics, type-operating trains, a plurality of tracker boards, connections from each pneumatic to said tracker boards, the connections between the type-trains and the tracker boards being permanent in character, whereby the control of the type operating trains by the tracker boards, is made absolute, master-advancing mechanism associated with each of said tracker boards, and means connected to said tracker boards to be controllable by the masters, for controlling said advancing mechanism.

86. A typewriter operator comprising two tracker boards, type-operating trains, a source of power permanently connected through the trains to the tracker-boards and a master device for each tracker board, one of said devices being in the form of an endless sheet, power-driven means capable of in predetermined alteration or sequence advancing said devices always forwardly, and means controllable by said endless device to suspend its own advance movement and simultaneously cause the advance of the other master device to be resumed.

87. A typewriter operator comprising two tracker boards and a master device for each tracker board, one of said devices being in the form of an endless sheet, power-driven means capable of alternately advancing said devices always forwardly, means controllable by said endless device to suspend its own advance movement and simultaneously cause the advance of the other device to be resumed, and means controllable by the last-mentioned device for suspending its own advance movement and simultaneously causing the advance of the endless device to be resumed.

88. A letter-writing apparatus comprising a typewriting machine, a tracker board, an endless master-sheet, said sheet having perforations or interruptions corresponding to the text of the letter to be written on the typewriting machine, means for advancing said sheet over said tracker board, a second master sheet having perforations or interruptions to correspond with a succession of addresses to be written on the respective let-

ters, means to advance said second master sheet over said second tracker board, means to coöperate with both said master sheets to operate the types of the typewriter, and means to coöperate with each of said master sheets during the advance thereof, for suspending its own advance and causing the other to resume its advance.

89. In a typewriter operator, the combination with a constantly revolving drive, of an endless master sheet, means connected to said driver for advancing said master sheet always in the same direction, permanently established means to coöperate with said master sheet for operating the typewriting machine, and means to suspend the advance of said endless master sheet while the driver continues in operation.

90. In a typewriter operator, the combination with a constantly revolving driver, of an endless master sheet, means connected to said driver for advancing said master sheet always in the same direction, permanently established means to coöperate with said master sheet for operating the typewriting machine, and means controlled by said endless master sheet for suspending the advance thereof while said driver continues in operation.

91. In a typewriter operator, the combination with a constantly revolving driver, of an endless master sheet, means connected to said driver for advancing said master sheet always in the same direction, permanently established means to coöperate with said master sheet for operating the typewriting machine, means to suspend the advance of said endless master sheet while the driver continues in operation, and means operated by said driver for operating the typewriter while the advance of said endless master sheet is suspended.

92. In a typewriter operator, the combination with a constantly revolving driver, of an endless master sheet, means connected to said driver for advancing said master sheet in a single direction, permanently established means to coöperate with said master sheet for operating a typewriting machine, a second master sheet, means connected to said driver for advancing said second master sheet always in the same direction, and means to coöperate with each master sheet to disconnect its own advancing means from the driver, and connect said driver to the advancing means of the other master.

93. The combination of a tracker board, master-sheets therefor, means, including a feed member, for advancing an endless master sheet over said tracker board, a second tracker board, means, including a feed member, for advancing a master sheet over said second tracker board, means connected to said tracker boards to operate the types of a

typewriter, a continuously rotating driver, and means for operatively connecting said advancing members in alternation to said driver, to advance each master sheet always 5 in a single direction while the advance of the other master sheet is suspended.

94. The combination with a typewriting machine, of trains of devices for operating a typewriting machine, a continuously rotating driver, an endless master sheet feedable always forwardly by said driver, a second master sheet also feedable always forwardly by said driver, each of said sheets capable of controlling said trains, and means controllable by each sheet for suspending the feed thereof by said driver, and causing the feed of the other sheet by said driver to be resumed.

95. A typewriter operator comprising a 20 set of type-operating trains, a source of power permanently connected to said trains and tending constantly to operate them, an endless master sheet, a second master sheet, means to coöperate with said sheets to enable 25 either of them to select the train to be operated by said source of power, power-driven means to advance said sheets, and means to enable each sheet to suspend its own advance and cause the advance of the other 30 sheet to be resumed.

96. A typewriter operator comprising a set of type-operating trains, selectively controllable means to actuate them, a member to return the carriage of the typewriter, 55 master sheets to control the selection of the type-operating trains, power-driven means to advance the master sheets, and means controllable by said master sheets for operating said carriage-returning member.

97. A typewriter operator comprising a set of type-operating trains, selectively controllable means to actuate them, a member to return the carriage of the typewriter, a master sheet to control the selection of the 45 type-operating trains, a constantly-revolving power-driver, means connected to said driver to advance the master sheet, means controllable by said master sheet for connecting said power-driver to said carriage-returning member, and means for suspending 50 said advancing means during the return of said carriage.

98. A typewriter operator comprising a set of type-operating trains, selectively controllable means to actuate them, a traveling member to return the carriage of the typewriter, a support upon which said traveling member is mounted and along which it travels, said traveling member connected to 60 the carriage to be moved in one direction thereby, a constantly-revolving power driver, means connectible thereto for causing said traveling member to return the carriage, a master sheet to control the selection of the type-operating trains, and means con-

trollable by said master sheet for causing the carriage to be returned by said power-driven member.

99. A typewriter operator comprising a set of type-operating trains, selectively controllable means to actuate them, a traveling member to return the carriage of the typewriter, a support upon which said traveling member is mounted and along which it travels, said traveling member connected to the carriage to be moved in one direction thereby, a power-driver, means connectible thereto for causing said traveling member to return the carriage, a master sheet to control the selection of the type-operating trains, and means controllable by said master sheet for causing the carriage to be returned by said power-driven member, and for suspending the operation of said master sheet during said return of the carriage. 85

100. A typewriter operator comprising a set of type-operating trains, a source of power directly connected to said trains and tending constantly to operate them, a master sheet means to coöperate with the master sheet to enable it to select the trains to be operated by said source of power, a continuously-rotating driver, means connected to said driver and also controllable by the master sheet for returning the carriage of the typewriter, and means also connected to said driver for advancing the master sheet. 95

101. A typewriter operator comprising a set of type-operating trains, a source of power directly connected to said trains and tending constantly to operate them, a master sheet means to coöperate with the master sheet to enable it to select the trains to be operated by said source of power, a continuously-rotating driver, means connected to said driver and also controllable by the master sheet for returning the carriage of the typewriter, means also connected to said driver for advancing the master sheet, and means connected to said carriage-returning means for suspending the advance of the master sheet during the return of the carriage. 105

102. A typewriter operator comprising a set of type-operating trains, a source of power directly connected to said trains and tending constantly to operate them, a master sheet means to coöperate with the master sheet to enable it to select the trains to be operated by said source of power, a continuously-rotating driver, means connected to said driver and also controllable by the master sheet for returning the carriage of the typewriter, means also connected to said driver for advancing the master sheet, means connected to said carriage-returning means for suspending the advance of the master sheet during the return of the carriage, and means dependent upon the completion of the 130

return of the carriage for causing the advance of the master sheet to be resumed.

103. A typewriter operator comprising a set of type-operating trains, a source of power directly connected to said trains and tending constantly to operate them, a master sheet, means to coöperate with said master sheet to enable it to select the trains to be operated by said source of power, a continuously-operating driver, a carriage-returning member operable thereby, a power-driven mechanism tending constantly to operate said carriage-returning device, means connected to said driver for advancing said sheet, and means to enable said sheet to restrain the operation of said power-driven carriage-returning mechanism until the proper time.

104. A typewriter operator comprising a set of type-operating trains, a source of power directly connected to said trains and tending constantly to operate them, a master sheet, means to coöperate with said master sheet to enable it to select the trains to be operated by said source of power, a continuously-operating driver, a carriage-returning member operable thereby, a power-driven mechanism tending constantly to operate said carriage-returning device, means connected to said driver for advancing said sheet, means to enable said sheet to restrain the operation of said power-driven carriage-returning mechanism until the proper time, and means for suspending the advance of the sheet during the return of the carriage.

105. A typewriter operator comprising a set of type-operating trains, a source of power directly connected to said trains and tending constantly to operate them, a master sheet, means to coöperate with said master sheet to enable it to select the trains to be operated by said source of power, a continuously operating driver, a carriage-returning member operable thereby, a power-driven mechanism tending constantly to operate said carriage-returning device, means connected to said driver for advancing said sheet, means to enable said sheet to restrain the operation of said power-driven carriage-returning mechanism until the proper time, means for suspending the advance of the sheet during the return of the carriage, and means for automatically causing the advance of the sheet to be resumed after the return of the carriage.

106. A typewriter operator comprising a set of type-operating trains, a master sheet, means to coöperate with said sheet to control the selection of the type-operating trains, means to operate the type-operation trains, a revolving power-driven device, means operable by said power-driven device to advance said master sheet, and means controlled by the master sheet to connect said

power-driven device to the typewriter carriage to return the latter.

107. A typewriter operator comprising a set of type-operating trains, a master sheet, means to coöperate with said sheet to control the selection of the type-operating trains, means to operate the type-operating trains, a power-driven device, means operable by said power-driven device to advance said master sheet, and means controlled by the master sheet to connect said power-driven device to the typewriter carriage to return the latter, and concomitantly suspend the advance of said master sheet.

108. A typewriter operator comprising a set of type-operating pneumatics, a tracker board connected thereto, a master sheet to run over the tracker board, a continuously operating driver, means connected to said driver to feed the master sheet over the tracker board, a power-driven carriage-returning device, and a pneumatic connected to said returning device and also connected to said tracker board.

109. A typewriter operator comprising a set of type-operating pneumatics, a tracker board connected thereto, a master sheet to run over the tracker board, a continuously operating driver, means connected to said driver to feed the master sheet over the tracker board, a power-driven carriage-returning device, a pneumatic connected to said returning device and also connected to said tracker board, and means also connected to said carriage-returning pneumatic for silencing said sheet-feeding means.

110. A typewriter operator comprising a set of type-operating pneumatics, a tracker board connected thereto, a master sheet to run over the tracker board, a continuously operating driver, means connected to said driver to feed the master sheet over the tracker board, a power-driven carriage-returning device, a pneumatic connected to said returning device and also connected to said tracker board, means also connected to said carriage-returning pneumatic for silencing said sheet-feeding means, and means called into operation automatically at the conclusion of the return of the carriage for causing said sheet-feeding means to resume operation.

111. The combination of a set of type-operating trains, a plurality of master sheets, means to feed the master sheets, means to coöperate with the master sheets to control said type-operating trains, power-driven means to return the typewriter carriage, and means to coöperate with said master sheets to silence said sheet-feeding means, to cause said power-driven means to return the carriage, and to cause said sheet-feeding means to resume operations.

112. The combination of a set of type-op-

erating trains, a master-sheet, a second master sheet, feeding means for said master-sheets, means for coöperating with said master-sheets to control the operation of said type-operating trains, a mechanism for returning the typewriter carriage, and means for enabling said carriage-returning mechanism to be controlled by either of said master-sheets.

10 113. The combination of a set of type-operating trains, a master sheet, a second master sheet, feeding means for said master-sheets, means for coöperating with said master-sheets to control the operation of said type-operating trains, a mechanism for returning the typewriter carriage, and means controllable by either of said master-sheets to start said carriage-returning mechanism into operation and concomitantly to suspend 20 its own feeding movement.

114. The combination of a set of type-operating trains, a master sheet, a second master sheet, feeding means for said master-sheets, means for coöperating with said master-sheets to control the operation of said type-operating trains, a mechanism for returning the typewriter carriage, means controllable by either of said master-sheets to start said carriage-returning mechanism into 30 operation and concomitantly to suspend its own feeding movement, and means brought automatically into operation at the conclusion of the return of the carriage for causing the feeding mechanism of the same master sheet to resume operation.

115. A typewriter operator comprising a set of type-operating trains, a source of power directly connected to said trains and tending constantly to operate them, a plurality of master sheets a plurality of tracker boards, connections from said source of power to said tracker boards, a power-driven carriage-returning device, and connections extending from said carriage-returning device 40 to said tracker boards to enable the master-sheet running over the tracker boards to control the return of the carriage.

116. A typewriter operator comprising a set of type-operating trains, a source of power directly connected to said trains and tending constantly to operate them, a plurality of tracker boards master devices, connections from said source of power to said tracker boards, a power-driven carriage-returning device, means for feeding said master devices independently over said tracker board, means extending to said tracker boards, to be controlled by the devices, for controlling the starting and stopping of 50 said feeding means and means for connecting up the power-driven carriage-returning device.

117. A typewriter operator comprising a set of type-operating trains, a source of power directly connected to said trains and

tending constantly to operate them, a plurality of master sheets a plurality of tracker boards, a power-driven carriage-returning device, means for feeding the master sheets, and means controllable by either sheet to suspend 70 its own advance and cause the carriage-returning device to operate.

118. A typewriter operator comprising a set of type-operating trains, a source of power directly connected to said trains and tending constantly to operate them, a plurality of master sheets a plurality of tracker boards, connections from said source of power to said tracker boards, a power-driven carriage-returning device, means for feeding 75 the master sheet, means controllable by either sheet to suspend its own advance and cause the carriage-returning device to operate, and means dependent upon the return of the carriage for causing the same sheet to resume 80 its advance.

119. The combination of a typewriting machine having a carriage, an endless master sheet, an operating mechanism for said typewriter controllable by said endless master sheet, and including power-driven means to feed the master sheet, means to coöperate with the master sheet to suspend the operation of the master sheet feeding means and concomitantly return said carriage, and 90 means dependent upon the return of the carriage for causing the sheet feeding means to resume operation.

120. The combination of a set of type-operating trains, a tracker board; an endless 100 master sheet; means to advance said endless master sheet over said tracker board; and means, including a part extending to said tracker board, for enabling the master sheet to suspend its advance and concomitantly 105 cause the return of the typewriter carriage.

121. The combination of a set of type-operating trains, a tracker board; an endless master sheet; means to advance said endless 110 master sheet over said tracker board; means, including a part extending to said tracker board, for enabling the master sheet to suspend its advance and concomitantly cause the return of the typewriter carriage, and 115 means dependent upon the completion of the return of the carriage for causing the advance of said master sheet to be resumed.

122. The combination of a set of type-operating trains, a tracker board; an endless master sheet; means to advance said endless master sheet over said tracker board; means including a part extending to said tracker board, for enabling the master sheet to suspend its advance and concomitantly cause 120 the return of the typewriter carriage, and means to enable the master sheet to advance 125 independently of the return of the typewriter carriage.

123. A typewriter operator comprising a 130

source of power, type operating trains extending to said source of power and including members that are permanently connected to said source of power; a master device; 5 an independent master device; and means to coöperate with said master devices, to enable either of them to select the trains to be operated by said source of power.

124. A typewriter operator comprising a 10 source of power, type operating trains extending to said source of power, the members of said trains being permanently connected to said source of power; a master device; a second master device; and independent 15 means coöperating with said master devices whereby either of said master devices may be made according to a predetermined arrangement, to select the type trains to be actuated by said source of power.

125. A typewriter operator comprising a 20 source of power, type operating trains extending to said source of power; a master device, the members of said trains being established in permanent power transmitting 25 relation between the master device and the source of power, whereby the application of the source of power to any predetermined train is absolutely controlled by said master device, a second master device similarly es- 30 tablished, and means coöperating with said master devices whereby according to predetermined characteristics of said means either of said master devices may be brought into

operative control of the power source, to the exclusion of the other master device. 35

126. A typewriter operator comprising a set of pneumatics, type-operating trains, a plurality of tracker boards, and permanently established connections from each pneumatic to said tracker boards. 40

127. A typewriter operator comprising a set of pneumatics, type-operating trains, a plurality of tracker boards, a sheet-advancing mechanism associated with each of said tracker boards, pneumatics to control said 45 sheet-advancing mechanism, and permanently established connections from said pneumatics to said tracker boards.

128. In a machine for operating a typewriter having upper and lower case shifts, 50 the combination with type-operating trains, a tracker board connected to said trains, and master-sheet advancing means, of means extending to said tracker board for operating the case-shifting mechanism of the typewriter, and including independently operable devices, one for operating the case-shift lock of the typewriter, and the other for releasing said lock. 55

In testimony whereof, we sign this specification in the presence of two witnesses.

LYMAN R. ROBERTS.
